(57) **CLAIM**

The ornamental design for a corner panel with the sensor for air conditioners, as shown and described.

DESCRIPTION

FIG. 1 is a front, left side and top perspective view of a corner panel with the sensor for air conditioners, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a reference horizontal cross-sectional view thereof; taken along line 8-8 of FIG. 2, with the internal system omitted;

FIG. 9 is a reference perspective view showing a state of use; and,

FIG. 10 is a reference top plan view showing a state of use. The broken lines in all views are shown for illustrative purposes only and form no part of the claimed design.

The alternate long and short dash line indicates the boundary of the claimed design.
